UNITED STATES PATENT OFFICE.

CHARLES SPRATT, OF NEW CROSS GATE, COUNTY OF KENT, ENGLAND.

SPEED-INDICATOR.

SPECIFICATION forming part of Letters Patent No. 404,992, dated June 11, 1889.

Application filed February 25, 1889. Serial No. 301,011. (No model.) Patented in England February 4, 1888, No. 1,711; in France February 13, 1889, No. 196,060, and in Belgium February 15, 1889, No. 85,016.

To all whom it may concern:

Be it known that I, CHARLES SPRATT, electrician, a subject of the Queen of Great Britain, residing at 9 Erlanger Road, New Cross Gate, in the county of Kent, England, have invented certain new and useful Improvements in Speed-Indicators, (for which I have received Letters Patent in Great Britain, No. 1,711, of February 4, 1888; in France, No. 196,060, of February 13, 1889, and in Belgium, No. 85,016, of February 15, 1889,) of which the following is a specification.

This invention has for its object improvements in speed-indicators. The apparatus is so arranged that it can be made to show at any time when required the speed of rotation of a steam-engine or other machine in connection with which the indicator may be applied. The indicator is in two parts. One, which I call the "transmitter," is in the immediate vicinity of the engine or machine. The other, which I call the "receiver," is in any place where it may be convenient that the indication should be given. The two parts are connected by electric circuits. When desired, two or more receivers can be used in connection with one transmitter. In the transmitter there is a clock-train. It is retained by a pawl, and it commences to run when the retaining-pawl is lifted. This is done by an electro-magnet, the circuit through which is closed by means of a press-button in the receiver whenever the mechanism is required to operate. The clock-work runs for a short time, long enough for the count to be made, and is then stopped by the pawl. The clock-work is controlled by a fan or other regulator, and its speed is accurately adjusted by duly proportioning the dimensions of the fan. In the clock-work there is an axis with two cams upon it, which, when the axis rotates, operate to close gaps in electric circuits connecting the two parts of the apparatus. One of these circuits I call the "counting-circuit." Its duty is to operate the counting-wheels; and the other circuit I call the "replacing-circuit." Its duty is to set the counting-wheels to zero. The gap in the replacing-circuit is closed by the operation of the cam soon after the clock-work is started, and the

setting of the counting-wheels to zero is then performed, as hereinafter described. It is not until this operation is completed and the replacing-circuit is again open that the other cam closes the gap in the counting-circuit and keeps it closed during a definite accurately-measured interval—for example, a quarter of a minute. In the counting-circuit, however, there is a second gap, which is closed at intervals by another cam, and this cam is on an axis driven by the engine or machine the speed of which has to be ascertained. This cam may be so made that it closes and opens the gap four times in each revolution.

The operation of the transmitter is thus as follows: The observer of the receiver starts the clock-work by pushing in the press-button provided for the purpose. As soon as the clock-work commences to run it sends a current of sufficient duration through the replacing-circuit. Then for a given interval (say a quarter of a minute) the apparatus sends a succession of currents (say four for every revolution of the engine) through the counting-circuit. The counting-circuit is afterward held open continuously and the clock-work is brought to rest. Two alternative courses are provided for the completion of the counting-circuit. It passes in one course when the engine is going ahead and in the other course when the engine is going astern. This is effected by providing in the transmitter a rocking contact-blade. It is fixed upon a boss, through which the axis driven by the engine passes. The friction between the boss and the revolving axis holds the blade against a contact-stud and completes the circuit. When the engine is reversed, the boss with the blade turns with the axis through a small angle sufficient to cause the blade to pass from one contact-stud to another.

Provision is made for the automatic winding of the clock-work by means of the engine.

The receiver contains the following parts: the starting-key, the counting mechanism, the mechanism for replacing the counting-wheels to zero, and the indicator for showing whether the engine is running ahead or astern. The starting-key is a simple mechanism closing

the call-circuit when a press-button is pushed in. The counting mechanism comprises an electro-magnet in the counting-circuit, an armature, and a propelling-arm operated there-by and driving a ratchet or propelling wheel, with which a counting-train is geared.

The replacing mechanism comprises an electro-magnet and armature operating a sliding bar which controls the positions of the counting-wheels, taking them out of gear with each other and with the driver and returning them into gear as required. The replacing mechanism also comprises another electro-magnet and armature, giving movement to another sliding bar or set of bars, which operate with cams upon the axes of the counting-wheels. These cams are of heart-like form, but flattened at the base. Each axis has such a cam upon it, and there is a corresponding bar working with the cam. When the edge of the bar lies against the flat of the cam, the axis is locked at the zero position of the counting-wheel; but by the endwise movement of the bar a recess in it is brought opposite to the cam and the axis is then free to turn. The movement of the bar in the opposite direction brings the end of the recess against the cam, and by its pressure it turns the cam until the zero position is reached. When the replacing current from the transmitter reaches the receiver, it first causes the counting-wheels to be thrown out of gear by exciting one of the electro-magnets above mentioned, and then the armature of this magnet makes a contact which enables the replacing-current also to flow in the coils of the electro-magnet which moves the replacing-bars. When the replacing-current ceases, springs bring back the sliding bars, the axes of the counting-wheels again fall into gear, and the recesses in the replacing-bars take such positions as to leave the wheels free to turn.

The indicator which shows whether the engine is running ahead or astern consists of two electro-magnets opposite to each other and with an armature between them. The counting-current passes through one or other of these, according to the course by which this current reaches the receiver, and then this magnet attracts the armature. The armature carries a toothed arc gearing with a pinion, and the axis of the pinion carries a light dial on which the words "Ahead" and "Astern" are written. One or other of these signs is brought opposite to an aperture in the fixed dial of the instrument, according to the position given to the movable dial.

In order that my invention may be fully understood and readily carried into effect, I will proceed to describe the drawings hereunto annexed.

In the drawings, Figure 1 is an elevation, with parts removed, of the portion of the transmitter containing the axis driven by the engine or machine, also the parts for opening and closing the counting-circuit a suitable

number of times during each rotation of the said axis, and the apparatus for directing the counting-current into one or other of two paths, according to the direction of rotation of the axis. Fig. 2 is a plan of the same parts. Fig. 3 is a plan of the portion of the transmitter containing the clock-work, the starting and stopping electro-magnet and parts connected therewith, and the cams and other parts closing a gap in the counting-circuit for a prearranged time, and also the mechanism for closing the replacing-circuit at the time when it is required to operate. Fig. 4 is an elevation of the same with parts removed. Fig. 5 is a plan of part of the clock-winding mechanism. Fig. 6 is an elevation of the same. Fig. 7 is a plan, and Fig. 8 is an elevation, of other parts of the winding mechanism. Fig. 9 is a front elevation of the receiver with its case removed. Fig. 10 is a side elevation of the same with the case in section. Fig. 11 is a section on the line 11-11 in Fig. 10. Fig. 12 is a side view of the axis of one of the counting-wheels with the parts mounted thereon. Fig. 13 is a front elevation, with parts removed. It shows particularly the heart-cam on the axis of the counting-wheel and the sliding bar which replaces the axis in the zero position. Fig. 14 is an elevation of the bars which carry the axes of the counting-wheels at their inner ends. Fig. 15 is a horizontal section of these bars. Fig. 16 shows the bars in another position as they are when holding the wheels in gear. Fig. 17 is an elevation showing the face of the receiver, and some other parts are also indicated. Fig. 18 is a section showing the press button and parts in immediate connection therewith, and also the magnet by which the counting-wheels are taken out of gear. Fig. 19 is a diagram illustrating the general arrangement of the parts and circuits.

In Figs. 1 and 2, *a* is an axis on which is a small belt-pulley. It receives a driving-strap passing also around a corresponding pulley on the shaft or axis of the engine or machine. In the case of a steam-engine it is convenient to pass the strap around the main shaft.

a' is a cam on the axis *a*. It operates against a small roller *b'* at the extremity of a spring-arm *b*. The arm *b* is fixed upon a block of vulcanite or other insulating material, and so is also another arm *c*. The arms *b* and *c* carry contacts, which are brought together when the cam acts upon the arm *b*, and which separate when the roller *b'* drops into the hollows of the cam. Adjusting-screws are provided, as the drawings indicate. The springs *b* and *c* are in the counting-circuit, and when they are separated the circuit is open.

d is a boss, of insulating material, loose on the axis *a*. It is pressed by the spring *d'* against the side of the cam *a'*. The boss carries a blade *d''*, and this makes contact with one or other of the studs *d³* *d⁴*, according to the direction in which the axis *a* is running. The blade *d''* is connected with one or other

of the springs b and c , and it carries the current which it receives from them to one or other of the studs d^3 . From these studs circuit-wires pass to the electro-magnet which operates the direction-indicator in the receiver. A spur-wheel a^2 is provided on the axis a , and a pinion on the axis a^3 gears with it. When the apparatus is used with machines running at high velocities, the driving-pulley is shifted from the axis a to the axis a^3 .

In Figs. 3 and 4, e is the spring-barrel, and e^x is the fusee of the clock-work. On the axis of the fusee and driven by it is a wheel with one hundred and forty-four teeth. It drives a pinion with twelve teeth, and on the same axis with this is another wheel with one hundred and forty-four teeth driving another pinion with twelve teeth. This latter is on the cam-axis f of the transmitter. The cam-axis is geared with a fly g by a train consisting of a wheel of one hundred and twenty teeth, a pinion of ten teeth, another wheel of ninety-six teeth, and a pinion of eight teeth, which last is on the axis of the fly.

g' is a disk on the fly-axis. It is provided with a single tooth, and with this the end of a pawl-lever h engages.

i is an electro-magnet. The circuit through it is closed by the press-button in the receiver. It then attracts its armature, lifts the lever h , and allows the clock-train to start. There is also a lever h' , having its fulcrum at h^2 , and this is also lifted by the armature of the electro-magnet. It carries at its end a roller, which is received into a recess in the edge of a disk on the cam-axis f . These parts serve to relieve the strain which would be thrown on the clock-work if it were stopped only at the fly-spindle. The cam-axis f has cams f' and f^2 mounted upon it, and these, when the axis rotates, operate against rollers at the ends of the spring-arms k' and k^2 . When these arms are lifted, they make contact with the arms k'^x and k^2x , respectively. Through k' and k^2x the replacing-circuit is closed, and this, as will be seen from the form and position of the cam f' , takes place immediately after the clock-work starts, and the contact lasts for a short time only. k^2 and k^2x are not closed together until the clock-work has run for a little time and has attained a steady velocity. This contact continues for exactly a quarter of a minute or some other pre-arranged time. During this interval electric impulses pass through the counting-circuit, traversing the springs k' and k^2x .

In Figs. 5 and 6, l shows an axis, which is arranged in line with the fusee of the clock-train. Upon the axis l two belt-pulleys l' l'' are mounted to run loosely. They are driven continuously by two straps, one direct and the other crossed. These straps also pass around the main shaft of the engine, or are actuated in other convenient manner. Each wheel l' carries a pawl l^2 and a spring l^3 , and the pawl engages with a corresponding ratchet fast upon the axis l , so that the said

axis is always driven in the same direction, whichever way the motor turns.

In Figs. 7 and 8, m is the end of the fusee-axis of the clock-work, and m' is a ratchet-wheel mounted loosely upon it and clutched with axis l , so that the wheel m' rotates continuously.

n is a toothed wheel mounted to turn freely upon m . It has one hundred and twenty teeth and gears with an intermediate wheel with forty teeth, which also engages with another wheel o of forty teeth fast with a wheel of forty-eight teeth, which gears with the toothed driving-wheel of one hundred and forty-four teeth on the fusee-axis. Thus when the clock runs the wheel n is slowly driven.

n' is an arm fixed to the wheel n , and it carries the pin n^2 .

m^2 is an arm fast upon the axis m . It carries the pawl m^3 and the spring m^4 , which, pressing against shoulders on the pawl, holds it either in or out of gear. The pin n^2 , when it comes round, acts against the tail m^{3x} of m^3 , and the pawl m^3 and strikes it into gear. Then the fusee-axis is carried round with the wheel m' until a rotation is nearly completed, when the tail m^{3x} again comes against the pin n^2 , but on the other side, and the pawl is thrown out by it. Thus the clock is wound one turn at a time.

In the receiver (see Figs. 9, 10, 11, 12, 13, 14, 15, 16, and 17) p is the electro-magnet which actuates the counting-wheels. Its armature p' has a propellent-arm p^2 , which, operating in the well-known manner, rotates a propellent-wheel p^3 on an axis q . There is also a ratchet-wheel upon the axis and a retaining-pawl.

q^2 is a spur-wheel on the same axis. It engages with and drives a corresponding wheel on the axis r , which is the first axis in the counting-train. In the counting-train there are three axes r , r' , and r^2 , and these are geared together in a well-known manner, so that as the axis r completes its rotation, which it does by ten successive steps, it moves the axis r' one step, equal to a tenth of a rotation, and similarly as the axis r' completes a rotation it moves the axis r^2 one step. There is a disk r^4 on the axis r , and against the periphery of this disk projections on another disk carried by the axis r' bear, so that this axis is locked and cannot turn until a notch in the disk r^4 comes round and allows one of the projections of the axis r' to pass. At the same time, also, a pin r^5 on the disk r^4 comes against a tooth on the disk carried by the axis r' , and so this axis is moved one step and then is again locked. Similarly the axis r' locks and propels the axes r^2 , r^3 , r^{3x} , and r^{3xx} are the indicating-wheels which these axes carry, one figure on which is visible through an aperture in the dial of the instrument, as is seen in Fig. 17. Thus the figures visible on this dial indicate the number of steps made by the propellent, and these correspond to the rotations of the engine or ma-

chine, which can be thus counted up to the number of nine hundred and ninety-nine in the minute.

The axes r , r' , and r^2 , at their outer ends, are carried by the links s s s , and at their inner ends they turn in bushes t t t on the links, which bushes are held between two bars u and v . The bar u is fixed and might be part of the instrument; but the bar v is able to slide to and fro a short distance under the influence of the spring v' and the electro-magnet w . The armature of this magnet is mounted on an axis which is provided with an arm w' , and this arm is jointed to the bar v . The bars u and v are both provided with elongated holes, into which the bushes t t t are received, and when the bar v is moved by the magnet it carries the bushes with it; but from the arrangement of the slots they are moved different distances. The axes r , r' , and r^2 are moved with the bushes, and so, when the magnet w operates, all the axes are taken out of gear, and when it ceases to operate they are returned into gear by the spring. When the arm w' has taken the wheels out of gear, it completes a contact at x , and then the electric current is divided between the magnet w and the magnet y . The magnet y has an armature z , carried by arms on the axis z' , on which is also a lever, z^2 . An arc of teeth z^2x on the lever z^2 gears with a pinion A , and on the same axis with this pinion there is a toothed wheel A' , gearing with rack-teeth B' on the bar B . In the bar B there is a recess B^2 , and when the axis r of the first counting-wheel leaves its zero position the cam C on this axis enters the recess B^2 , which, however, is of such dimensions that the rotation of the axis r is not interfered with; but when, the count having been made, the bar B is moved by the magnet the shoulder B^{2x} at the end of the recess comes against the cam C , and, the axis being now out of gear, the cam is turned until the axis reaches the zero position. The upper edge of the bar passes the flat of the cam, and the axis is so held as long as the bar retains its position. When the electric current ceases, the two electro-magnets release their armatures, and the axes fall into gear again and are set free. There are other bars B^x and B^{xx} attached to the bar B , and these operate in a similar manner with heart-cams C on the axes r' and r^2 .

55 D' D² are two electric magnets, through one or other of which the counting-current reaches the receiver, and E is the armature which they control. It is upon a lever which also carries the arc of teeth E', gearing with a

pinion F', which is upon the same axis with 60 the movable dial F, on which the words "Ahead" and "Astern" are printed, and, as seen in Fig. 17, one or other of these words becomes visible through an aperture in the stationary dial of the receiver.

G is the press-button which closes the starting-circuit.

Fig. 19 is lettered in accordance with the preceding description as far as the diagrammatic nature of this figure admits.

What I claim is—

1. A speed-indicator, substantially as described, consisting in a transmitter and receiver connected by electric circuits, and comprising clock-work which for a certain time allows a counting-circuit to be completed, a contact-maker actuated by the engine or machine and operating to close and open the counting-circuit during the interval allowed by the clock and more or less frequently in accordance with the speed of the engine or machine, an electro-magnet or electrical mechanism operated by the closing and opening of the counting-circuit, counting-wheels driven by such magnet or mechanism, and apparatus replacing the counting-wheels to the zero position after use and ready to again operate.

2. A speed-indicator, substantially as described, consisting in a transmitter and receiver connected by electric circuits, and comprising mechanism which for a certain time allows a counting-circuit to be completed, a contact-maker actuated by the engine or machine and operating to close and open the counting-circuit, an electro-magnet or equivalent mechanism operated by the closing and opening of the counting-circuit, counting-wheels operated by such mechanism, and a circuit-closer in the receiver in circuit with an electro-magnet or equivalent mechanism in the transmitter operating to start the mechanism when its indication is required.

3. The mechanism, substantially as described, for replacing the counting-wheels, consisting of parts which move the wheels into and out of gear with each other and with the driver, and cams on the axes of the wheels, and bars operating in conjunction with such cams to turn the wheels to the zero positions and to release them when they have again passed into the zero position.
